His Attorney

Patented Dec. 13, 1927.

1,652,905

UNITED STATES PATENT OFFICE.

NICHOLAS J. McMAHON, OF BALTIMORE, MARYLAND, ASSIGNOR TO GENERAL ELECTRIC COMPANY, A CORPORATION OF NEW YORK.

SKID.

Application filed September 15, 1924. Serial No. 737,672.

My invention relates to the construction of skids and an object of my invention is to provide a skid which is simple, strong and durable and may be manufactured at a minimum cost.

My invention will be better understood from the following description taken in connection with the accompanying drawing, and its scope will be pointed out in the appended claim.

Referring to the drawing Fig. 1 is a top plan view of a skid involving my invention. Fig. 2 is a side elevation of the same and Fig. 3 is an end elevation.

In the drawing, the top 1, which for example, may be constructed of heavy wooden planks, is secured in any suitable manner to longitudinal stringers 2 thus forming the platform of the skid. Adjacent each of the four corners of the platform is a foot 3 which is formed up from sheet metal, a steel stamping for example. The metal strip forming each foot is given two approximately right angle bends 4 at points spaced from each other and spaced from its middle portion. In order that the bottoms of these feet shall have a rounded or convex bearing portion, the material forming the strip is made to swell outwardly both between the two bends 4 as shown in Fig. 3 and between opposite edges as shown at 5 in Fig. 2.

At its upper end each side portion of each foot is given an offset 6 thereby forming an inwardly extending shoulder upon which rests a stringer 2. Each foot is shown secured to a stringer by means of two bolts 7 having nuts 8 by which the foot may be firmly clamped against opposite sides of a stringer and in such a position that the bottom face of the stringer rests upon the shoulder formed in the foot.

What I claim as new and desire to secure by Letters Patent of the United States is:—

A skid comprising a platform formed of a plurality of stringers and a top secured thereto, a plurality of supporting feet each comprising a one piece, transversely arranged sheet metal strip bent substantially U-shaped, the upper end portions of each being flat and having offsets forming shoulders engaging lower edges of the stringers, and means for clamping said end portions to opposite sides of the stringers, the lower portion of each foot having two substantially right angle bends, the material between the bends swelling outwardly to form a convex bearing surface.

In witness whereof, I have hereunto set my hand this 9th day of September, 1924.

NICHOLAS J. McMAHON.
